CLAIM

The ornamental design for a fitness wheel with visual indicators, as shown and described.

DESCRIPTION

FIG. 1 is a perspective view of a fitness wheel with visual indicators according to our new design;

FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

FIG. 7 is a bottom view thereof. The portions of the design shown in broken lines are for illustrative purposes only and form no part of the claimed design.

The dot-dash lines define the bounds of the claimed design and form no part thereof.

1 Claim, 7 Drawing Sheets
